UNITED STATES PATENT OFFICE.

EUGENE DE KLEIST, OF NORTH TONAWANDA, NEW YORK.

AUTOMATIC MUSICAL INSTRUMENT.

SPECIFICATION forming part of Letters Patent No. 726,701, dated April 28, 1903.

Application filed January 21, 1902. Serial No. 90,639. (No model.)

To all whom it may concern:

Be it known that I, EUGENE DE KLEIST, a citizen of the United States, residing at North Tonawanda, in the county of Niagara and State of New York, have invented new and useful Improvements in Automatic Musical Instruments, of which the following is a specification.

This invention relates to automatic pianos and similar musical instruments in which the sound-producing parts are controlled by a pneumatic-action, my improvements being applicable to so-called "piano-players," which operate upon the keys of an ordinary piano, as well as to self-playing pianos, in which the pneumatic-actuating devices are combined with the usual piano-action.

The principal object of my invention is to simplify the construction and improve the arrangement of the parts of the pneumatic-actuating devices with a view of reducing their cost, rendering the same more compact and direct in action, and facilitating access to the parts for repairing and renewing the same.

Another object of the invention is to provide the pneumatic-action with a simple tracker or controlling mechanism which may be operated by a rotary pin-barrel.

In the accompanying drawings, consisting of four sheets, Figure 1 is a fragmentary vertical section of an automatic piano operated by a pin-barrel embodying my improvements. Figs. 2, 3, and 4 are fragmentary horizontal sections in lines 2 2, 3 3, and 4 4, Fig. 1. Figs. 5 and 6 are vertical sections in lines 5 5 and 6 6, Fig. 1. Fig. 7 is a fragmentary vertical section of a piano-player constructed according to my invention, the plane of section being in line 7 7, Fig. 8. Fig. 8 is a fragmentary vertical section in line 8 8, Fig. 7. Fig. 9 is a fragmentary vertical section showing a modified construction of the exhaust and vent valves.

Like letters of reference refer to like parts in the several figures.

Referring to the construction shown in Figs. 1 to 6, A indicates the upper portion of the case of an automatic piano, which is operated by a rotary pin-barrel B, arranged in the case. The instrument may have a piano-action of any ordinary construction, the latter forming

no part of my invention and being therefore not shown in the drawings.

C is a main wind or exhaust chest arranged lengthwise in the case A on the rear side of the pin-barrel B and having an exhaust channel or duct d, by which it is connected with a bellows or other exhaust device. (Not shown in the drawings.)

E represents motor-pneumatics which operate vertical rods or stickers E', which latter in turn actuate the usual jacks or equivalent parts of the piano-action, the movable boards of these pneumatics having extensions e, which strike the lower ends of the stickers E'. These pneumatics are preferably arranged outside of the wind-chest to facilitate access to the same for repairing and renewing them when necessary and are secured to the under side of horizontal wind boards or shelves e', which extend lengthwise of the exhaust-chest C and are secured to the rear wall of the latter. One of these motor-pneumatics is provided for each sticker, and the same are arranged in as many rows or tiers as necessary and preferably in stepped order to secure compactness. Each of these pneumatics is connected with an independent valve-case or small auxiliary exhaust-chest F by a horizontal channel e² in the corresponding wind-board e', a vertical channel e³ in the rear wall of the main exhaust-chest, and ports e⁴, formed in the front and rear walls of the last-named channel, as shown in Fig. 1. The valve-cases F communicate both with the main exhaust-chest C and the atmosphere by ports or openings f f', and in the construction shown in the drawings each valve-case is composed of two sections which are applied to opposite sides of the rear wall of the exhaust-chamber, so that the case is arranged partly inside and partly outside of the exhaust-chest. The exhaust and vent openings f f' are formed in the front and rear walls of the valve-cases, as shown.

Each row of motor-pneumatics has a companion row of such valve-cases located immediately below the same, and the rear wall of the exhaust-chest C is preferably composed of independent sections F', arranged one above another and each carrying a row of motor-pneumatics and their complementary valve-cases F, as shown in Fig. 1. These valve-cases are

also arranged in stepped or staggered relation, as seen in Fig. 5, and the vertical ducts or channels e^3 of adjoining sections are correspondingly offset, so that the ends of said channels are closed by the solid portions of the adjacent sections, as shown in Fig. 6.

The exhaust and vent openings ff' of each valve-case are controlled by valves $g\ g'$, which in the construction shown are hinged at their upper ends, so as to swing vertically, and arranged within the case so as to close in opposite directions against the inner sides of said openings. Between these valves is interposed a horizontal rod h , which transmits motion from one valve to the other in such a manner that when the exhaust-valve g is opened the vent-valve g' is closed, and vice versa. To prevent binding, this valve-rod preferably bears loosely against the backs of the valves. It passes through the apertures e^4 of the channels e^3 and slides in transverse guide-bars h' , which bridge said apertures, as seen in Figs. 1, 2, 5, and 6. As shown in Fig. 5, these guide-bars preferably extend continuously across a number of the apertures e^4 in the same horizontal row in order to simplify the construction of the action.

In order to insure a tight closure of the exhaust-valves g , the adjacent front walls of the valve-cases are inclined rearwardly, so as to overhang, as shown in Fig. 1. By this construction the depending exhaust-valves by their tendency to hang in a vertical position closely hug the valve-seats formed by the inclined walls.

The opening and closing movements of the valves may be controlled by any suitable means, but the valves are preferably operated by the following mechanism: Each of the exhaust-valves g is provided with a rigid opening rod or stem i , which extends forwardly through the corresponding exhaust-opening f and bears loosely against a flexible diaphragm or pneumatic j , the diaphragm being preferably provided centrally with a rigid disk j' , which receives the wear of said stem. This diaphragm forms the rear wall of an air-chamber j^2 and is attached at its edge to a ring or frame j^3 , which forms the sides of said chamber. This ring is secured to the front wall of the exhaust-chest C , which wall forms the front wall of the air-chamber or pneumatic j . Each of these air-chambers communicates with the surrounding main exhaust-chest by a small hole or duct j^4 , formed in the ring j^3 . The air-chambers or valve-operating pneumatics j communicate also with the outer atmosphere by individual ducts or channels k , arranged in the adjacent front wall of the main chest C , the outer ends of these channels terminating at the upper end of said wall in the construction shown in the drawings. The admission of the atmosphere to these channels and the corresponding pneumatics j is controlled by valves l , which may be termed "tracker-valves" and which are applied to the upper ends of the channels, as

shown in Fig. 1, each channel being provided with such a valve. These tracker-valves are closed by springs l' and opened by the pins and staples of the rotary pin-barrel B through the medium of keys or trip-fingers n and stickers o . These trip-fingers rock upon a pivot-rod n' and are vibrated by the pins and staples of the barrel in a common manner. It will now be understood that the pin-barrel causes the tracker-valves l to control the channels k , and these parts thus perform the office of the usual perforated music-sheets used in connection with tracker-boards. The pin-barrel has the advantage of being more durable than a music-sheet.

The operation of my improved pneumatic-action is as follows: When the inlet end of a tracker-channel k is closed by its tracker-valve l , the air is exhausted therefrom and from the corresponding diaphragm-chamber j through the small hole j^4 of said chamber, and as the pressure against both sides of the companion diaphragm is balanced under these conditions the diaphragm is moved to the position shown by dotted lines in the middle diaphragm in Fig. 1 by the weight of the closed exhaust-valve g and the open vent-valve g' , which is exerted upon the diaphragm through the rods $h\ i$. As the exhaust-valve of the motor-pneumatic is now closed and the corresponding vent-valve open, the motor-pneumatic is cut off from the main exhaust-chest C and remains in its normal expanded condition, in which it does not operate the corresponding sticker E' . When the tracker-valve l of a channel k is opened, as shown by full lines in Fig. 1, the atmosphere enters that channel and the chamber j^2 , to which it leads, and presses the corresponding diaphragm j rearwardly to the reverse position shown by full lines in connection with the upper diaphragm in Fig. 1. This reversed diaphragm acting upon the stem i pushes the exhaust-valve g open, and this valve acting upon the rod h at the same time closes the vent-valve g' , thereby placing the corresponding motor-pneumatic E in communication with the main exhaust-chest and cutting off the outer atmosphere therefrom. The air is now exhausted from said motor-pneumatic and the latter collapsed by the atmospheric pressure, thus lifting the companion sticker E' and causing the latter to operate the corresponding hammer of the piano-action. It will be observed that the stickers E' are actuated by the collapsing movement of the motor-pneumatics. As soon as the corresponding tracker-valve l is again closed the motor-pneumatic E is allowed to expand and the sticker allowed to descend to its former position. The rear wall of each valve-case F , against which the vent-valve g' seats itself, is preferably inclined rearwardly, as shown in Fig. 1, so that this valve when released tends to swing away from said wall. By this construction when the tracker-valve l is closed the vent-valve g' by its weight promptly

begins the closing movement of the companion exhaust-valve g , the atmospheric pressure against the vent-valve g' assisting in this movement.

- 5 As the motor-pneumatics E are arranged outside of the wind or main exhaust chest, they are readily accessible for making repairs and renewals when necessary, and by arranging the valve-cases F partly outside of 10 the wind-chest access can be had to their interior by simply removing the rear sections, which latter may be screwed in place or otherwise made removable. By making the rear wall of the exhaust-chest in sections, each 15 of which carries a row of motor-pneumatics and their companion valve-cases F , the parts can be conveniently assembled and cheaply constructed, and they are at the same time readily accessible.
- 20 By my improved arrangement the motor-pneumatics also act directly upon the stickers E' , rendering the action simple in construction.

When my improvements are embodied in 25 a piano-player, the tracker-ducts k' are controlled by the usual perforated music-sheet B' , as shown in Fig. 7. In this case the rows of motor-pneumatics E^2 are arranged in the upper portion of the inclosing case above the 30 rows of valve-cases F^2 and connected with the latter by independent air-ducts e^5 , arranged as shown in Fig. 8 or in any other suitable manner. The stickers E^3 must in this case receive a downward impulse in order to de- 35 press the piano-keys P , and the position of the motor-pneumatics is therefore reversed from that shown in Figs. 1 to 6; so that their movable boards are caused to swing downward and bear upon the upper ends of the 40 stickers when the pneumatics are collapsed, as shown in Fig. 7. In other respects the construction of the action may be like that shown in Figs. 1 to 6.

While I prefer to incline the front wall of 45 the valve-cases F and employ a swinging exhaust-valve g , that wall may be vertical and a sliding disk valve g^2 used, as shown in Fig. 9, if desired. In this case the disk valve is secured to a continuous valve-stem h^2 , which 50 bears at its ends against the diaphragm j and the vent-valve g' .

I claim as my invention—

1. The combination with a wind-chest, a sound-controlling member, and a motor-pneumatic for operating said member, of a valve-chamber communicating with the motor-pneumatic and provided in opposite walls with exhaust and vent ports opening into said chest and the atmosphere, respectively, 55 oppositely-opening valves applied to said ports, a sliding rod or sticker arranged between said valves and bearing loosely against both of the same, and an actuating device for said valves, substantially as set forth.
- 65 2. The combination of an exhaust-chest having a channeled wall divided horizontally into separate, superposed sections, two or

more rows of motor-pneumatics, and two or more rows of corresponding valve-cases connected with said pneumatics by the channels 70 in said wall and each having an exhaust-port connecting with said exhaust-chest, a vent-port which opens into the atmosphere, and oppositely-opening valves applied to said ports, each of said channeled-wall sections 75 carrying a row of said motor-pneumatics and their complementary row of valve-cases, substantially as set forth.

3. The combination with an exhaust-chest and a sound-controlling member, of a motor-pneumatic for operating said member, a valve-case arranged partly inside and partly outside of said chest and communicating with the motor-pneumatic and provided within the chest with an exhaust-port and outside thereof with 80 a vent-port, oppositely-opening valves applied to said ports and operating in unison, and an actuating device for said valves, substantially as set forth.

4. The combination with an exhaust-chest, 90 a sound-controlling member and a motor-pneumatic for operating said member, of a horizontal valve-case communicating with said motor-pneumatic and having a vent-port and an inclined, overhanging wall provided 95 with an exhaust-port, a depending valve applied to said port and hinged to the inner side of said overhanging wall, and a valve applied to said vent-port and opening in the reverse direction from said exhaust-valve, substantially as set forth.

5. The combination with an exhaust-chest, a sound-controlling member and a motor-pneumatic for operating said member, of a horizontal valve-case communicating with 105 said motor-pneumatic and having an inclined, overhanging wall provided with an exhaust-port which communicates with said exhaust-chest and an opposing wall inclined in the same direction and containing a vent-port, 110 depending exhaust and vent valves applied to said ports, respectively, and hinged to the inner sides of said inclined walls, and means for operating said valves in unison, substantially as set forth.

6. The combination with an exhaust-chest, a sound-controlling member and a motor-pneumatic for operating said member, of a horizontal valve-case, communicating with 120 said motor-pneumatic and having an exhaust-port which communicates with said exhaust-chest and an inclined wall provided with a vent-port, a swinging vent-valve applied to said vent-port on the inner side of said inclined wall, and an exhaust-valve applied to 125 said exhaust-port and opening in the reverse direction to said vent-valve, substantially as set forth.

7. The combination with a wind-chest having a channeled wall and a number of sound-controlling members, of motor-pneumatics for operating said members, a plurality of valve-cases communicating with said pneumatics through the channels of said wall and through

opposing apertures in the walls of said channels, horizontal guide-bars extending continuously across a number of said apertures, each of said valve-cases being provided with exhaust and vent ports communicating with said wind-chest and the atmosphere, respectively, and oppositely-opening valves applied to said exhaust and vent ports and a valve-rod arranged between the valves of each case and sliding in said guide-bars, substantially as set forth.

8. The combination with an exhaust-chest and a sound-controlling member, of a motor-pneumatic for operating said member, a valve-case arranged partly inside and partly outside

of said chest and communicating with the motor-pneumatic and provided within the chest with an exhaust-port and outside thereof with a vent-port, oppositely-opening valves applied to said ports and operating in unison, an actuating-pneumatic for said valves having a vent or tracker duct, a tracker-valve controlling said duct, and means for operating said tracker-valve, substantially as set forth. 20

Witness my hand this 15th day of January, 25
1901.
